No. 1228

Francis J. Peirce, of Lowell, Mass.
Assignor to Roxbury Carpet Company, of Boston.
Letter Patent No. 1228, dated April 3, 1860.

The schedule referred to in these Letters Patent and making part of the same.

To all Persons to whom these Presents shall come:

Be it known that I, Francis J. Peirce, of Lowell, in the County of Middlesex and State of Massachusetts, have invented an ornamental design to be wrought into Carpets or other Fabrics, and I do hereby declare that the same is represented in the annexed photographic drawing.

The said design I claim as my invention.

Witnesses.
